UNITED STATES PATENT OFFICE.

WILLIAM E. MOORE, OF PERU, ILLINOIS; HARRIET L. MOORE EXECUTRIX OF SAID
WILLIAM E. MOORE, DECEASED.

REGENERATOR-FURNACE.

1,117,219.

Specification of Letters Patent. Patented Nov. 17, 1914.

Application filed January 26, 1914. Serial No. 814,283.

To all whom it may concern:

Be it known that I, WILLIAM E. MOORE, a citizen of the United States, residing at Peru, in the county of La Salle and State of Illinois, have invented certain new and useful Improvements in Regenerator-Furnaces, of which the following is a full, clear, concise, and exact description, reference being had to the accompanying drawings, forming 10 a part of this specification.

My invention relates to an improved form of regenerator furnace in which several regenerators are disposed side by side to supply heated gas and air to the furnaces associated with the regenerators to heat the furnaces, the products of combustion from the furnaces being conducted through certain of the regenerators at the same time to heat them and thus store a large amount of the 15 heat contained in the products of combustion for the purpose of subsequently heating the gas and air delivered to the furnaces. By my invention means are provided for using certain of the regenerators at one time 20 for heating the gas and air, at which time the other regenerators are used to store the heat of the products of combustion as the exhaust gases pass on their way to the stack; and devices are employed for reversing these 25 conditions as desired, so that the regenerators first used to heat the gas and air may subsequently be employed to receive and store the heat of the exhaust gases, at which time the regenerators previously employed 30 to thus store the heat contained in the exhaust gases are employed to heat the gas and air delivered to the furnaces.

Another feature of my invention consists in disposing the inlet and outlet passages 40 opening into the furnaces so that the burning gases may take the shortest possible path from the inlet openings to the outlet openings that will properly heat the contents of the furnaces, as a result of which the burning 45 gases are most effectively employed in heating the furnaces. Furthermore, by my invention I dispose the passages for the gases in such a manner between two adjacent furnaces that the air and gas supplied 50 to the furnaces are divided between the two adjacent furnaces and the products of combustion are received from the two furnaces by common passages in the otherwise solid partition wall separating these two adjacent 55 furnaces. These passages in the partition

wall lead downward to the regenerators located side by side underneath the furnaces and in this manner I am able to produce a very compact arrangement of furnaces and regenerators which not only effectively utilizes the fuel employed for heating the furnaces, but also utilizes a minimum amount of floor space.

The present invention is an improvement upon the construction of furnace shown and 65 described in United States Letters Patent No. 750,868, issued February 2, 1904, to Philip A. MacKay and myself.

The several drawings illustrating my invention are as follows:

Figure 1 shows in vertical transverse sectional view, two adjacent furnaces and the associated regenerators in accordance with my invention, this section being taken along the line 1—1 in Fig. 2. Fig. 2 is a longitudinal sectional view of one of the furnaces and regenerators taken along the line 2—2 in Fig. 1. Fig. 3 is a plan view of the stack for receiving the exhaust gases from the regenerators, together with the valve mechanism for controlling the flow of air and gas to the regenerators and the flow of the exhaust gases from the regenerators to the stack. Fig. 4 is a sectional view of the parts shown in Fig. 3 taken along the line 4—4. 85

Similar numerals refer to similar parts throughout the several views.

As shown in Figs. 1 and 2, my furnace and regenerator construction consists in a plurality of longitudinal chambers 1, 2, 3 90 and 4 located in the base of the structure, said regenerators being filled with brick checker-work, as is usual in the construction of these devices. These regenerators have extending underneath them passageways 5, 95 6, 7 and 8 for supplying air and gas to the regenerators or conducting from them the products of combustion, as the case may be. Above the regenerators two furnaces 9 and 10 are disposed which are similarly constructed, except that they are the reverse of each other, and these furnaces are separated by a central partition wall 11. This partition wall 11 has formed in it a plurality of series of communicating passageways connecting the furnaces 9 and 10 with the regenerators 1, 2, 3, and 4. As each series of passageways is identical with each other series, but one will be described, it being understood that one series after another is em- 100 105 110

ployed throughout the entire length of the furnaces which are of substantially the same extent longitudinally as the regenerators under them. The regenerator 1 is connected by the passageway 12 with the upper portion of each of the furnaces 9 and 10, the upper end of this passageway being shown at 12^a in Fig. 2; the regenerator 2 is connected by a passageway 13 with the upper portion of each of the furnaces 9 and 10, the upper end of this passageway being indicated in Fig. 2 at 13^a; the regenerator 3 is connected by the passageway 14 with the lower portion of each of the furnaces 9 and 10, the upper end of this passageway being indicated in Fig. 2 at 14^a, and the regenerator 4 is connected with the lower portion of each of the furnaces 9 and 10 by the passageway 15, the upper end of this passageway being indicated in Fig. 2 at 15^a. It will be understood that the passageways opening into each of the furnaces 9 and 10 follow each other in the same sequence in each series, and that the first passageway 25 of each series communicates with the regenerator 3, the second of each series communicates with the regenerator 4, the third of each series communicates with the regenerator 2, and the fourth of each series communicates with the regenerator 1. It will be further observed that all of the passageways communicating with the regenerators 3 and 4 terminate in the lower portion of each furnace, whereas the passageways extending from the regenerators 1 and 2 terminate in the upper portion of the furnaces. It will further be observed that the passageways extending upward through the partitions 11 are as close together as they can be placed in view of the construction of the furnaces and that, therefore, the action of each regenerator upon the furnace, whether in supplying air or gas or receiving the products of combustion from the furnace, is equalized throughout the entire length of the furnace.

Furnaces of the kind under consideration are commonly employed for the reduction of ore and for smelting operations, and in the furnaces shown in Fig. 1 crucibles 16 and 17 are indicated in the position that they assume in the furnaces to be heated by the action of the burning gases therein.

As clearly shown in Fig. 1, each of the passageways extending upward through the partition 11 is branched at its upper end so that one path extends to the furnace 9 and the other path extends to the furnace 10. In this manner, each passageway serves to simultaneously supply to each furnace air or gas or to receive from both furnaces the products of combustion, as the case may be. Since the outlet openings of the passageways are in the same vertical wall of each furnace and are immediately adjacent to

the passageways extending vertically through the partition 11, the distance that the burning gases and products of combustion are required to travel through the passageways in going from the supply regenerators to the receiving regenerators is reduced to a minimum. 70

As shown in Fig. 3, the passageways or flues 5, 6, 7 and 8 are extended beyond the furnace and regenerator to the controlling mechanism indicated in plan view in Fig. 3 and in elevation view in Fig. 2. This controlling mechanism is constructed as follows: The central flues 6 and 7 are branched and diverted outwardly in the manner indicated in Fig. 3 and terminate in either side of a valve casing 18 located immediately over the ends of said flues. The casing 18 contains a butterfly valve 19 secured to a shaft 20 extending through the casing and provided with an operating wheel 21 by which the valve may be caused to assume either the position shown in full lines or the position shown in dotted lines in Fig. 4. 80 A passageway 22 is provided in the masonry immediately below the valve 19 between the ends of the flues 6 and 7, which passageway extends into the bottom of the stack 23, as indicated in Fig. 3. The flues 5 and 8 are also spread outwardly so as to pass around the spread ends of the flues 6 and 7 and are continued beyond the stack 23 and terminate below and communicate with either end of a valve casing 24 similar to the valve casing 18 and provided with a similar valve 25 90 adapted to be operated by a hand-wheel 26. The valve casing 24 communicates by means of a passageway 27 in the masonry below the valve 25 with the opposite side of the stack 23 to that with which connection is 95 made by the passageway 22. The valve casings 18 and 24 have located above them chambers 28 and 29 communicating with the upper part of the corresponding valve casings through openings, as shown for the 100 valve casing 18 at 30 in Fig. 4, and these chambers are supplied with gas and air respectively by any suitable means, not shown, and the gas and air as thus supplied may be under any desired pressure. It is immaterial which chamber is supplied with air and which supplied with gas, as the operation of the mechanism is the same in either event. 105

The operation of the device is as follows: Assuming that the chamber 28 is supplied with gas and the chamber 29 with air and that both of the valves or dampers 19 and 25 are in the position indicated in Fig. 4 in full lines, gas is supplied to the flue 6 and air is supplied to the flue 5 under such 115 pressure as may be necessary to properly supply the furnaces through the regenerators. At this time both of the flues 7 and 8 are in communication with the stack 23. The gas supplied to the flue 6 is sent through 120

125

130

the regenerator 2 to the third outlet opening, designated 13^a, of each series of outlet openings in each of the furnaces 9 and 10; the air supplied to the flue 5 is sent through the regenerator 1 to the fourth outlet opening in each of the furnaces, designated 12^a in Fig. 2, and at each pair of outlet openings 13^a and 12^a combustion of the gas takes place, being supported by the air referred to. The gases of combustion pass downward for this condition in each furnace to the openings 14^a and 15^a at the upper ends of the passages 14 and 15 by which the exhaust gases are conducted to the regenerators 3 and 4 respectively. After passing through these regenerators, the exhaust gases pass through the flues 7 and 8, and thus out into the stack 23. The continued operation of the furnaces for this adjustment of the valves 19 and 25 continues until the checker-work in the regenerators 3 and 4 has been heated to a point where it will not effectively absorb more of the heat of the exhaust gases, at which time the valves 19 and 25 are turned to their reverse position, which connects the flues 5 and 6 with the stack 23 and supplies gas to the flue 7 and air to the flue 8. For this condition of the valves, gas is delivered to each of the furnaces through the first of each series of openings, designated 14^a, and air is supplied to each furnace through the second of each series of passageways, designated 15^a, and combustion now takes place between each such pair of openings in each of the furnaces and the products of combustion pass upward around the retorts 16 and 17 to the other passageways 12^a and 13^a of each series, from which the products of combustion are communicated through the passageways 12 and 13 to the regenerators 1 and 2 respectively to heat the checker-work in said regenerators. After passing through this checker-work, the gases of combustion pass outward through the flues 5 and 6 to the stack. It will be observed that for this condition the gas and air supplied to the furnaces is caused to pass through the previously-heated checker-work of the regenerators 3 and 4, and is thus preheated to a considerable degree before the gas is burned, which results in utilizing a large portion of the heat of the gases of combustion. The reversal of the valves 19 and 25 may be made at any desired intervals, so as to secure the most effective operation of the apparatus.

While in the drawings there are two separate shafts shown supporting the valves or dampers 19 and 25 so that they may be independently operated, if for any reason it is desired to do so, since these devices are preferably operated at the same time, they may be connected by any desired mechanism so that the operation of one of these valves or

dampers will operate the other, as, for example, by a continuous shaft supporting both of them or any suitable gearing connecting the separate shafts.

As a result of the construction and operation above-described, it will be observed that all of the parts involved in supplying gas and air to the furnaces or in removing the products of combustion therefrom are located on a lower level, thus making the communication between the supply chambers and the regenerators and between the regenerators and the stack as direct as possible. Furthermore, it will appear that the regenerators may be constructed so as to be of substantially the same width as the furnaces located over them, as a result of which the maximum width of the structure need not exceed that required for the furnaces themselves, and thus a considerable saving in floor space is effected.

While I have shown my invention in the particular embodiment herein described, I do not, however, limit myself to this construction, as I may use other and equivalent constructions without departing from the spirit of my invention.

What I claim is:

1. In a regenerative furnace, the combination of two furnaces disposed side by side and separated by a single partition wall, and a plurality of series of passageways in the partition each opening into both furnaces, corresponding ones of the passageways of the several series serving to supply fuel to the furnaces and the remaining ones of each series serving to remove the products of combustion from the furnaces, and devices for reversing the operation of the passageways.

2. In a regenerative furnace, the combination of two furnaces disposed side by side and separated by a single partition wall, a plurality of series of passageways in the partition each opening into both furnaces, corresponding ones of the passageways of the several series serving to supply fuel to the furnaces and the remaining ones of each series serving to remove the products of combustion from the furnaces, and a plurality of regenerators each connected with corresponding ones of the several series of passageways.

3. In a regenerative furnace, the combination of two furnaces disposed side by side and separated by a single partition wall, a plurality of series of passageways in the partition each opening into both furnaces, corresponding ones of the passageways of the several series serving to supply fuel to the furnaces and the remaining ones of each series serving to remove the products of combustion from the furnaces, and a plurality of regenerators each connected with corresponding ones of the several series of passageways.

- 4 sageways, said regenerators being located under the furnaces.
- 5 4. In a regenerative furnace, the combination of two furnaces disposed side by side and separated by a single partition wall, a plurality of series of passageways in the partition each opening into both furnaces, corresponding ones of the passageways of the several series serving to supply fuel to the furnaces and the remaining ones of each series serving to remove the products of combustion from the furnaces, a plurality of regenerators each connected with corresponding ones of the several series of passageways, said regenerators being located under the furnaces, and valve mechanism for supplying fuel to a first one or ones of said regenerators and for delivering the products of combustion from the furnaces through 10 the remaining regenerators. 70
- 15 5. In a regenerative furnace, the combination of a furnace having in one of its longitudinal vertical walls a plurality of series of vertical passageways, the openings of each series terminating in the furnace at different heights from those of the adjacent series, and devices for delivering fuel to the furnace through the openings of the series located at one level and removing the products of combustion from the openings located at another level. 75
- 20 6. In a regenerative furnace, the combination of a furnace having in one of its longitudinal vertical walls a plurality of series of vertical passageways, the openings of each series terminating in the furnace at different heights from those of the adjacent series, devices for delivering fuel to the furnace through the openings of the series located at one level and removing the products of combustion from the openings located at another level, and a regenerator connected with the openings of each level. 80
- 25 7. In a regenerative furnace, the combination of a furnace having in one of its longitudinal vertical walls a plurality of series of vertical passageways, the openings of each series terminating in the furnace at different heights from those of the adjacent series, devices for delivering fuel to the furnace through the openings of the series located at one level and removing the products of combustion from the openings located at another level, and a regenerator connected with the openings at each level, said regenerators located under said furnace. 85
- 30 8. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, and devices for delivering gas and air respectively to the two openings of each series located at the same level and connecting the two openings of each series at the other level with an exhaust passageway. 90
- 35 9. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, and devices for delivering gas and air respectively to the two openings of each series located at the same level and connecting the two openings of each series at the other level with an exhaust passageway, said devices serving to reverse the relation between the supply and delivery openings in the furnace as desired. 95
- 40 10. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, devices for delivering gas and air respectively to the two openings of each series located at the same level and connecting the two openings of each series at the other level with an exhaust passageway, and regenerators connected with similar ones of said series of openings. 100
- 45 11. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, devices for delivering gas and air respectively to the two openings of each series located at the same level and connecting the two openings of each series at the other level with an exhaust passageway, said devices serving to reverse the relation between the supply and delivery openings in the furnace as desired, and regenerators connected with similar ones of said series of openings. 105
- 50 12. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series. 110
- 55 13. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series. 115
- 60 14. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series. 120
- 65 15. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series. 125

symmetrically arranged throughout the successive series, devices for delivering gas and air respectively to the two openings of each series located at the same level and connecting the two openings of each series at the other level with an exhaust passageway, and regenerators connected with similar ones of said series of openings, said regenerators being located side by side under the furnace.

13. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, devices for delivering gas and air respectively to the two openings of each series located at the same level and connecting the two openings of each series at the other level with an exhaust passageway, said devices serving to reverse the relation between the supply and delivery openings in the furnace as desired, and regenerators connected with similar ones of said series of openings, said regenerators being located side by side under the furnace.

14. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, devices for delivering gas and

air respectively to the two openings of each series located at the same level and connecting the two openings of each series at the other level with an exhaust passage, regenerators connected with similar ones of said series of openings, said regenerators being located side by side under the furnace, and flues under said regenerators connecting them with said devices.

15. In a regenerative furnace, the combination of a furnace having vertical passageways in one of its longitudinal vertical walls arranged in a plurality of series, each series consisting of four passageways two of which open into the furnace at or near its bottom and the remaining two at or near the top of the furnace, said openings being symmetrically arranged throughout the successive series, devices for delivering gas and air respectively to the two openings of each series located at the same level and connecting the two openings of each series at the other level with an exhaust passageway, said devices serving to reverse the relation between the supply and delivery openings in the furnace as desired, and regenerators connected with similar ones of said series of openings, said regenerators being located side by side under the furnace, and flues under said regenerators connecting them with said devices.

In witness whereof, I hereunto subscribe my name this fourth day of December, A. D. 1913.

WILLIAM E. MOORE.
